(57) **CLAIM**

We claim the ornamental design for a cartridge label, as shown and described.

DESCRIPTION

This patent contains at least one drawing executed in color. Copies of this patent with a color drawing will be provided by the Office upon request and payment of the necessary fee. FIG. 1 is a top plan view of a cartridge label comprising our new design in accordance with a first embodiment of the present invention;

FIG. 2 depicts a top plan view of a second embodiment thereof;

FIG. 3 depicts a top plan view of a third embodiment thereof;

FIG. 4 depicts a top plan view of a fourth embodiment thereof;

FIG. 5 depicts a top plan view of a fifth embodiment thereof; FIG. 6 depicts a top plan view of a sixth embodiment thereof;

FIG. 7 is a top plan view of a seventh embodiment thereof;

FIG. 8 depicts a top plan view of an eighth embodiment thereof;

FIG. 9 depicts a top plan view of a ninth embodiment thereof;

FIG. 10 depicts a top plan view of a tenth embodiment thereof;

FIG. 11 depicts a top plan view of an eleventh embodiment thereof; and,

FIG. 12 depicts a top plan view of a twelfth embodiment thereof.

(Continued)

The broken lines shown in the drawings illustrate portions of the cartridge label that form no part of the claimed design.
